WAISTBAND CONSTRUCTION

Edward M. Singer, East Chicago, Ind., assignor to Silver Manufacturing Co., Chicago, Ill., a corporation of Illinois

Application March 23, 1955, Serial No. 496,263

4 Claims. (Cl. 2—236)

This invention relates to a garment construction and more particularly to a waistband construction for men's and women's garments.

In present garments provided with waistbands, the material of the garment is, at its upper end, turned over inwardly and is stitched to a stiffened inside waist band construction that it located very close to, if not at, the upper end of the garment. After a garment has been worn considerably, there is a tendency for the material at the upper end of the garment to stretch and roll over, thereby revealing the upper end of the inside waistband. If the waistband is of a different color than the garment material, as it is in the great majority of garments, the resulting effect is very unsightly.

In present garments provided with a stiffened waistband construction, there is provided, extending around the waist of the garment, an elongated band of stiffening material which is cross-cut relative to the length of the band of stiffening material, that is, the warp and woof of the band of stiffening material lies at an angle, of preferably 45 degrees, to the longitudinal edges of said band of stiffening material. This is desirable as it provides for some stretching of the waistband construction.

If the cross-cut band of stiffening material were merely made wider and extended above the normal waistband construction to provide means for stiffening the portion of the garment extending above said normal waistband construction, there would exist two problems. First of all, the extra portion of the cross-cut band would have a tendency, as is the tendency of all cross-cut stiffeners, to stretch. Such stretching would be undesirable and would result in the objectionable rolling over of the upper edge of the garment which has been described above. The second undesirable feature would lay in the existence of a visible stitch between the material of the garment and the upper edge of the normal waistband construction.

One of the objects of this invention is to provide a novel garment construction which obviates the above defined deficiencies existing in present waistband constructions.

Another object of this invention is to provide an improved garment construction which is provided with a normal cross-cut stiffened waistband construction spaced further below the upper edge of the garment than is presently provided, and providing novel means for stiffening the portion of the garment extending above said normal waistband construction.

Still another object of this invention is to provide a garment provided with a waistband stiffener construction additional to the normal cross-cut waistband construction and which additional waistband stiffener construction substantially eliminates any tendency thereof to stretch or roll over.

A further object of this invention is to provide a garment construction having an additional waistband stiffener construction extending upwardly of the normal cross-

2

cut waistband construction for the garment which additional stiffener assembly substantially resists stretching and which eliminates any unsightly visible stitching therefor.

5 And another object of this invention is to provide a new and improved waistband construction for garments which is characterized by its simplicity and inexpensiveness of construction.

Further objects and advantages of this invention will 10 become apparent as the following description proceeds and the features of novelty which characterize this invention will be pointed out with particularity in the claims annexed to and forming part of this specification.

A preferred embodiment of the invention is shown in 15 the accompanying drawings, in which:

Figure 1 is a perspective view of a pair of men's pants provided with the waistband construction of this invention.

Figure 2 is an enlarged cross-section view through the 20 waistband of the garment shown in Figure 1;

Figure 3 is an enlarged cross-section view showing the aligning of the various strips and pieces of fabric before they are stitched together to form the waistband construction of this invention; and

25 Figure 4 is an enlarged elevation view taken on line 4—4 of Figure 2 and shows the arrangement of threads of the cross-cut and straight-cut stiffener material strips, by means of which the improved waistband construction is obtained.

30 An essential feature of my invention lies in the use, as described hereinafter, of a band of cross-cut stiffener material for the normal waistband construction and the use of a band of straight-cut stiffener material for the additional waistband stiffener construction, said latter band of straight-cut material extending upwardly from the 35 upper edge of the normal waistband construction. In the particular embodiment, the stiffening material is cut so that the length of the additional stiffener band lies parallel to the warp and selvage of the stiffener material.

40 Referring now to the drawings, there is shown a pair of men's pants that are provided with the novel waistband construction of this invention. The waistband construction of this invention is not limited in its use to a particular type of garment and may also be used in other types of garments which employ waistband construction, such as women's skirts and slacks.

45 As shown in Figure 1, the men's pants include the garment cloth or material 10 which is folded to define an upper edge 12 of the garment, an elongated waistband generally indicated at 14, and a strip of garment material 16 which is located on the inside of the waist of the garment between the upper edge 12 of the garment and the upper longitudinal edge of waistband 14.

50 Referring to the details of the waistband construction which are most clearly shown in Figure 2, the outer side of the garment material is indicated by numeral 18. The waistband 14 is formed of an elongated strip of cross-cut felted canvas 20 (best shown in Figure 4) which is about 2½" wide and which is covered over the inside 55 surface thereof by a strip of twilled fabric 22. The lower longitudinal edge of the twilled fabric is wrapped around the lower longitudinal edge of the cross-cut canvas stiffener 20 and is secured in position by means of a line of stitching 24 which secures the overlapped twilled fabric to the canvas stiffener 18 on both sides thereof.

60 The upper longitudinal edge of the canvas stiffener is bent back to define a downwardly extending segment 26, and the upper edge of the twilled fabric 22 is also bent over to accompany the downwardly extending segment 26.

65 The waist terminal end 10a of the garment material 10 is positioned adjacent the downwardly extending segment 26 of stiffener material and is positioned so that

the overlapped segment of twilled material 22 is positioned between said segment 26 and the waist terminus 10a of the garment material. Positioned between the inside portion 16 of garment material and the outer side 18 of garment material is a second strip of straight-cut canvas stiffener material 28 which is best shown in Figure 4 and is approximately 1" in width. The longitudinal edges of the straight-cut band of stiffener material 28 are cut parallel to the warp and selvage of the sheet of material from which said band of stiffener material 28 is cut. The lowermost edge of the second straight-cut strip of stiffener material and the waist terminus 10a of the garment material, as well as the terminal edges of the twilled material 22 and felted canvas stiffener segment 26, are all substantially in alignment with each other, and all four layers of material are secured together by a single stitch 30 which extends through the four layers of material, and which is spaced about one-quarter (1/4) inch from the aligned terminal edges of the materials.

The arrangement above defined is such that the greater portion of the second straight-cut stiffener strip 28 extends upwardly from the seam 30, and is adapted to have the garment material wrapped therearound as shown in Figure 2 to define said inside band of garment material 16, which extends downwardly between the upper edge 12 of the garment and the upper edge of the waistband 14. By this arrangement, the cross-cut elongated band of stiffener material 20 still operates as the normal waistband construction and permits longitudinal stretching thereof, while the straight-cut elongated band of stiffener material 28 operates to substantially resist longitudinal stretching thereof, and thus there is avoided the unsightly appearance of a stretched, or rolled over, upper edge of a garment.

Figure 3 illustrates the arrangement of the various strips of material at a point during the assembly of the garment. It will be seen that in the step shown in Figure 3, the terminal edges of the four pieces of material including the second straight-cut stiffener 28, the first cross-cut stiffener 20, the twilled fabric 22, and the garment material 10, are in substantial alignment, and the stitch 30 is located approximately 1/4" away from the aligned edges and is put through all four thicknesses of material. Thereafter, the material may be creased so that the downwardly extending segment 26 of the stiffener material is formed and defined, and with the greater portion of the second stiffener strip 28 extending upwardly from the seam 30 as shown in Figure 2. When the garment is folded to the condition shown in Figure 2, no portion of the stitching, or seam, 30 is visible and this provides for a neater, more attractive, and desirable arrangement.

Figure 3 also shows, in dot and dash lines, the manner in which the layers of material are folded, after they are stitched together, so as to obtain the arrangement shown in Figure 2.

It can be seen from the foregoing description that there is provided by this invention a novel garment and waistband construction which provides a width of straight-cut stiffening in the garment which extends upwardly above the normal cross-cut stiffened waistband construction of the garment, thereby providing an increased effective width of stiffened waistband construction, and also providing for prevention of the unsightly effect which occurs in present garment constructions when the upper edge of the garment stretches, or rolls over, as is apt to occur after the garment has been subjected to considerable wear.

While there has been shown and described a particular embodiment of this invention, it will be obvious to those skilled in the art that various changes and modifications may be made therein without departing from the invention and, therefore, it is intended in the appended

claims to cover all such changes and modifications as fall within the true spirit and scope of the invention.

What I claim as new, and desire to secure by Letters Patent of the United States, is:

- 5 1. In a garment, which includes an elongated cross-cut stiffened waistband member secured to the inwardly and downwardly turned waist terminus of the garment material along a line spaced below the upper terminus of the garment, the improvement comprising an elongated straight-cut stiffener member extending along substantially the entire length of the cross-cut stiffened waistband member and extending upwardly from the stiffened waistband member between the outer body of the garment material and the inwardly and downwardly turned waist portion of said garment material, so that the material of said garment overlies said straight-cut stiffener member to side said stiffener member.
- 10 2. In a garment, which includes an elongated cross-cut stiffened waistband member secured to the inwardly and downwardly turned waist terminus of the garment material along a line spaced below the upper terminus of the garment, the improvement comprising an elongated straight-cut stiffener member extending along substantially the entire length of the cross-cut waistband member and secured to said stiffened waistband member outwardly thereof and along said line of securement between said waistband member and the waist terminus of the garment material, said straight-cut stiffener member extending freely upwardly from the stiffened waistband member between the outer body of the garment material and the inwardly and downwardly turned waist portion of said garment material, so that the material of said garment overlies and hides the straight-cut stiffener member including the upper free edge thereof.
- 15 3. In a garment construction, the combination comprising, a first elongated cross-cut stiffener strip that is turned back on itself along a longitudinal line thereon to define an elongated segment, a lining strip secured to said first stiffener strip and extending in overlapping relation to said segment of the stiffened strip, garment material positioned with a terminal waist portion thereof in overlapping relation to said overlapping portion of said lining, a second elongated straight-cut stiffener strip, of smaller width than the width of said first stiffener strip, overlying said garment material and aligned with said terminal waist portion of said garment material, whereby a portion of said second stiffener strip overlaps said overlapping portion of said lining, a line of stitching along said longitudinal line of the first stiffener strip securing said lining to said first stiffener strip to define a stiffened cross-cut waistband member, and securing said terminal waist portion of the garment material to the waistband member to define, in part, the garment waist, and securing said second straight-cut stiffener strip to the garment waist so that, when the garment material is turned back on itself in overlapping relation to said waistband member, the waist portion of the garment material is inwardly and downwardly turned and is secured to the stiffened waistband member along a line spaced below the upper terminus of the garment, and said second straight-cut stiffener strip extends freely upwardly and outwardly of the stiffened waistband member and is disposed between the outer body of the garment material and the inwardly and downwardly turned waist portion of said garment material, so that said stiffener strip is hidden by the garment material.
- 20 4. A garment comprising, in combination, an elongated first stiffener strip and an elongated lining strip superposed one upon the other and both arranged with one of their longitudinal edges substantially in alignment; an elongated portion of garment material, an elongated second stiffener strip superposed on a waist terminus portion of said garment material and both arranged with one of their longitudinal edges in substantial alignment with each other and with said aligned longitudinal edges

of said first stiffener strip and said lining strip; said strips of aligned material being stitched together along a line spaced from and substantially parallel to said aligned longitudinal edges, the portions of said first stiffener strip and of said lining strip, other than edge portions thereof located between said line of stitching and said longitudinal edges, defining an elongated stiffened waistband member which is bent back in overlapping relation with said edge portions thereof, and in overlapping relation with edge portions of the second stiffener strip and of the waist terminus portion of garment material located between said line of stitching and the longitudinal edges thereof; the remaining portion of said second stiffener strip extending freely upwardly from said line of stitching and oppositely from said stiffened waistband member and 15

being disposed outwardly thereof in the finished garment; and the waist portion of said garment material extending upwardly from the stiffened waistband and being turned outwardly around the free longitudinal edge of said second stiffener strip and overlapping said second stiffener strip and said stiffened waistband member to define an outer portion of the garment and to hide the second stiffener strip.
